UNITED STATES PATENT OFFICE.

SAMUEL W. TYLER, OF GREENWICH, NEW YORK.

IMPROVEMENT IN HARVESTERS.

Specification forming part of Letters Patent No. 30,651, dated November 13, 1860.

To all whom it may concern:

Be it known that I, SAMUEL W. TYLER, of Greenwich, in Washington county and State of New York, have invented certain new and useful Improvements in Harvesting-Machines adapted for harvesting all kinds of small grain and grasses; and I do hereby declare that the following is a full and exact description thereof, reference being had to the accompanying drawings, with the letters of reference thereon, making a part of this specification.

Similar letters refer to like parts of the machine.

Figure 1 is a view in perspective of a machine containing my improvements from the front, near the grain side thereof. Fig. 2 is a top or plan view thereof. Fig. 3 is a side elevation thereof, with the cutting apparatus folded in its rest by the side of the machine. Fig. 4 is a view of the automatically-adjustable head-piece, with its extension of a rigid arm. Fig. 5 is a view of a slotted hand-lever for raising the head-piece and cutting apparatus, with an automatically-adjustable point of leverage. Fig. 6 is a view of the inner end of the finger-beam, and a turn-plate, which are used in folding the cutting apparatus by the side of the machine, and in automatically elevating the front edge of the cutting apparatus. Fig. 7 is a view of the exterior of closed ratchet-boxes on the hubs of the drive-wheels. Fig. 8 represents a longitudinal view of the pitman-rod, with its intermediate swivel-joint and curve near the end next the cutter or sickle bar. Fig. 9 is a sectional view of a hollow or tubular pitman-rod.

My invention relates, first, to the construction of a harvesting-machine with an automatically-adjustable head-piece, which is vertically adjustable at the point of its attachment to the machine, and to which the cutting apparatus is attached, with an extension of a rigid arm laterally, and which rigid arm is hinged at its rear end to the rear corner of the frame of the machine, and which serves, besides bracing the head-piece, as a brace through the turn-plate and the inner shoe of the finger-bar, laterally bracing the finger-bar; secondly, to the construction of a turn-plate, which in the present case is arched on its outer line, and which is hinged on a strong bolt to the head-piece near its lower end, and is

also hinged at its front and rear ends to the shoe at the inner end of the finger-beam, and it is of a character to permit its independent upward oscillation to elevate the front edge of the cutting apparatus, as any abrupt elevations in the path of the machine may require, and it has a stop on its rear end, which, coming under a flange on the rigid arm, prevents the front edge of the cutting apparatus from turning down below a level, and which also permits the raising and folding of the cutting apparatus longitudinally in its rest by the side of the machine; thirdly, to providing an "iron hanger," so termed, for a rigid support of bearings for all the journals of the gear-work, so firm and rigid as not to be subject to warp or spring in the springing of the frame of the machine, so that they may preserve their relative positions toward each other, and not become bound or cramped in their action, which is suspended but firmly fastened to the cross-pieces A A', and also forms a strong additional brace to the frame itself; fourthly, to the provision of a slotted hand-lever, which, acting on a roller-fulcrum, is automatically adjustable in its point of leverage for raising the head-piece and cutting apparatus to pass over intervening obstructions.

That others skilled in the art may make and use my invention, I proceed to state the manner of its construction and the principle of its operation.

It has a main frame composed of the wooden cross-pieces A A' and the side pieces, B B', the latter of which are boxed on and firmly bolted to the former at the several corners of the frame. This frame is borne on the axle F of two driving-wheels, E E. These driving-wheels are placed on their axle just inside of the side pieces, B B'. An internal spur-wheel, S, is firmly secured to the axle F adjoining the driving-wheel on the stubble side of the machine, and in its revolutions with the axle it meshes into and revolves a pinion on the transverse pinion-shaft P, that on its other end carries a bevel-wheel, that in its revolutions revolves a bevel-pinion on the pitman-shaft, which, by a wrist on a disk or eccentric on its opposite end, through the pitman-rod K, vibrates the sickle-bar.

In my experience with harvesting-machines with wooden frames I have found that the gear-work was liable to become cramped and bound

in its action by the springing or warping of the frame, and when it becomes only slightly cramped or bound the action of the cutting apparatus is thereby rendered much less perfect, which I have found to be an evil of such magnitude as to be studiously avoided; and to avoid or prevent these evils I have provided that all the journals of the gear-work shall be borne on a single iron support or hanger, O, which in my machine consists of an iron bar with arms arching out on each side at either end, and which rise up and are firmly secured to the pieces A and A' of the frame, and is not subject to warping or being strained out of position by the springing or warping of the wooden frame, and hence their several bearings are kept in their relative positions toward each other and toward the other parts of the machine, and the iron hanger at the same time serves as a firm brace to the frame of the machine. I have also provided an improved automatically-adjustable head-piece, which is vertically adjustable at the point of its attachment to the machine, with an extension of a rigid arm laterally, which is hinged to the rear corner of the frame of the machine. The head-piece is marked G and the rigid arm of the head-piece is marked H. The rigid arm serves to give additional power of resistance to the head-piece in resisting any sudden or unusual strains, and, through its connection with the finger-bar the turn by plate M and the shoe I, it affords a lateral brace to the finger-bar also. The head-piece G rises and falls automatically, according to the undulations of the ground in the path of the machine, when it is used in harvesting grass or grain, and the part of the rigid arm next the head-piece participates in the motions of the head-piece, serving at the same time as its lateral brace, as before stated. I deem any further description of the function of my improved automatically-adjustable head-piece to be unnecessary.

The cutting apparatus is attached to the head-piece and to the pitman-rod by a flexible joint, which will permit it to decline from a position at right angles with the plane of the head-piece, or to rise to an angle less than a right angle, and still work with success. This connection is effected through the turn-plate M and the shoe at the inner end of the finger-bar. The turn-plate is of an arched form on its exterior line, and it is secured to the head-piece by a strong bolt, as represented in Fig. 1, and is permitted a free oscillation upward in front on said bolt, which serves as a swivel-joint, so that the front edge of the cutting apparatus may be turned up as any abrupt or sudden undulations in the path of the cutting apparatus might require, and a stop on the rear end of the turn-plate comes under the exterior flange on the rigid arm and prevents the front edge of the cutting apparatus from being turned down below a level; and by reference to Figs. 6 and 4 it will be perceived that they are provided with holes through them other than those by which they are fast-

ened together, the object of which is to regulate the degree of the oscillation of the turn-plate and the shoe at the inner end of the cutting apparatus as occasion may require; andt the number of holes for this purpose may be increased as may be deemed necessary, and those in the turn-plate should be in the form of a slot, so as at all times to permit a moderate amount of oscillation, as occasions arise in using harwesters when it is necessary to raise the cutting apparatus to avoid intervening obstacles; and to accomplish this purpose, inasmuch as the cutting apparatus is attached to the machine by a flexible joint, I have provided a lever, l, with convenient handles at its top, and which is turned down through the head-piece G and a fixed nut near its foot upon the inner end of the finger-bar to bring it into a rigid position at right angles to the plane of the head-piece, and when this result is attained I use the following-described devices to elevate the cutting apparatus.

The rear edge of the head-piece G is provided with ratchet-teeth of such peculiar form, as is represented in the drawings, that when the peculiarly-formed bite of the slotted hand-lever L, which is moved on a fulcrum-pin covered with a friction-roller attached to the side piece, B, is operated in connection with said teeth, they together form a connection in the form of an ordinary knuckle-joint, by which means the bite of the lever L is held to its position with a tenacity to compel such a working of the slotted lever L upon the friction-roller t as will lengthen or shorten the short part or end of the lever in proportion to the different positions which it may occupy in producing an upward or downward movement of the head-piece. The angular position of the handle of the lever L in relation to its slot is so arranged that by a downward inclination of the handle of the lever forward the bite of the lever will readily drop into its proper connection with the ratchet-teeth upon the head-piece. The inventor considers these features in their relations to each other as important, inasmuch as he is enabled thereby to use a lever disconnected from the head-piece, which allows a free and independent movement of the head-piece in the use of the machine while the lever remains at rest, and yet enables him to raise the cutting apparatus to any considerable height on any sudden emergency.

A ratchet of ordinary form is provided on the front edge of the head-piece, with a pawl hinged to a convenient position in front of it, to hold it in any convenient position when harvesting grain or when traveling.

In my experience in the use of harvesting machines I have observed that the resistance produced by them when in use is greatly increased or lessened as their vibrating parts are made light or heavy, and as the sickles are vibrated about sixty times per minute, if the pitman-rod and sickle-bar are lightened to the amount of ten pounds, the gear-works are re-

lieved of the resistance of vibrâting six hundred pounds per minute; and having this result in view I have constructed the sickle-bar in my machine so as to make it sufficiently strong, but as light as possible, and I have constructed my pitman-rod hollow or tubular, whereby the pitman-rod is not only made lighter by a large proportion, but is also rendered stronger.

In the course of my experience in the use of harvesting-machines I have found that ratchets by which to throw the driving-wheels out of gear with their axle, and were uncovered or unprotected, were liable to be obstructed in their action by the heads and stalks of grain or grass or any other obstructing matter, and though ratchets have been covered in other machines and when used on other parts of harvesting-machines, I have constructed mine on the hub of the driving-wheels of my machine, with internal ratchets provided with two or more pawls that are kept in position by springs, and I have covered them with collars on the axle of the driving-wheels, which protects them from any obstructing matter, also renders the construction of the machine less complex, and at the same time applies the power of the pawls more directly. The several pawls are provided with a pin extending through a slot in the collar, by which to throw them out of gear, when the drive-wheels will revolve freely on their axle in the transportation of the machine, said ratchets being held out of gear with the pawls by a button on the collar or cover of the ratchets. A spring on the cross-piece A, with a catch in it, holds the front end of a lever in place, which holds the gear-work in connection with the cutting apparatus, and is in a convenient distance from the feet of the driver to enable him, by a slight pressure by his foot, to depress the spring to throw it out of connection with the lever, when a spiral spring on the pinion-shaft instantly throws the gear-work out of connection with the cutting apparatus, which devices are represented in the drawings. Provision is also made for a driver's

seat by the erection of braces rising from the pieces A A', which support a rest for it; but a particular description of it and of the cutting apparatus, which is also represented, is not deemed to be important, further than to observe that the cutting apparatus is to be constructed with a particular regard to lightness and strength.

It is obvious that the position of the head-piece may be reversed so as to adjust the cutting apparatus at the rear end of the machine, or so modified as to make the attachment at almost any other point desired without departing from the principle of my invention.

Having thus fully stated my invention, what I claim therein as new, and desire to secure by Letters Patent, is—

1. The combination of the automatically-adjustable head-piece G and turn-plate M, or their equivalents, with the cutting apparatus, arranged and operating substantially as described.

2. The ironhanger D, for a common support for the journals of the pinion and pitman-shafts of a harvesting-machine, when used as a strong iron brace of a light wooden frame, in combination with such frame, substantially as described.

3. The hand-lever L, when constructed and used as specified, in combination with the cutting apparatus, for the purposes set forth, and substantially as described.

4. The adjusting-rod l or its equivalent, by the use of which the driver, while on his seat, may bring the cutting apparatus to a position at right angles to the head-piece, where it may be held, in combination with the head-piece and cutting apparatus, for the purpose set forth, and substantially as described.

In testimony of which invention I hereunto set my hand.

S. W. TYLER.
